UNITED STATES PATENT OFFICE.

EDGAR C. HILL, OF COLUMBUS, OHIO.

JAR-CLOSURE.

1,170,906.

Specification of Letters Patent.

Patented Feb. 8, 1916.

Application filed June 29, 1915. Serial No. 37,011.

To all whom it may concern:

Be it known that I, EDGAR C. HILL, a citizen of the United States of America, residing at Columbus, in the county of Franklin 5 and State of Ohio, have invented certain new and useful Improvements in Jar-Closures, of which the following is a specification.

The present invention appertains to an improved jar closure, and is designed to provide a device which is comparatively simple 10 in construction and operation, durable, and inexpensive in cost of production.

The primary object of the invention is the provision of a device capable of imparting 15 a wedge action to clamp the jar lid or top tightly upon its gasket in such manner that the device may be readily locked in place and with equal facility be unlocked when desired to open the jar.

20 The invention consists in certain novel combinations and arrangements of parts of a "spider" lock as will be hereinafter more fully set forth.

The accompanying drawings depict the 25 best mode I have so far devised for the practical application of the principles of my invention, in which—

Figure 1 is a side view of the top part of a glass or other jar having its lid locked by 30 my device. Fig. 2 is a sectional view showing a part of the device to illustrate the "wedge" action of the closure in clamping the jar top to the jar. Fig. 3 is a top plan view of the device locked on a jar. Fig. 4 35 illustrates the same device unlocked.

In the preferred embodiment of the invention as illustrated in the drawings I employ a bridge piece formed with two arms 1 and 2 and each of these arms is fashioned with 40 a hook as 3, while the extremity of each arm is beveled as at 4. A third arm 5 completes the three points of attachment of the locking device, and this arm is also hooked at 7 and provided with a beveled end 8 similar 45 to the formation of the ends of the bridge piece. Thus we have a triangular formation of the locking device and the three beveled ends are adapted to clamp the jar top 8' down upon the gasket 9 on the jar 10, utilizing the 50 beveled ring 11 under the flange 12 at the

mouth of the jar. To accomplish this clamping function I employ a lever pivoted at 13 on the bridge piece whose handle is provided by the long arm 14 and the short arm 15 of this operating lever is pivotally connected 55 at 16 to the movable arm 5.

The operation and functions of the device are graphically illustrated in the drawings wherein Fig. 4 shows the device unlocked and Fig. 3 illustrates the locked position. 60 The two hooks of the bridge piece are first slipped over the jar top to be clamped with their beveled ends under the beveled ring 11 of the jar and then the loose hook 7 is positioned as in Fig. 4. The operating lever 65 handle 14 is then turned on its pivot 13 to swing the pivot point 16 around, and past a line made by the two pivot points and the hook 7, in other words beyond the dead center. It will be noted that the operating lever 70 is permitted to swing under the pivoted end of the pivoted arm 5 and the pivoted end of the arm is offset for this purpose forming a shoulder 5' against which the operating lever is brought when its short arm has been 75 brought beyond the dead center. In this manner the lever is held in position and the hooks are locked about the jar top. The action of the lever draws the hooked end 7 of the pivoted arm toward the bridge piece and 80 the consequence is that the three beveled ends 4, 4 and 7 of the clamp arms are frictionally engaged and drawn under the beveled ring 11 of the jar with the result that the top is clamped down tightly upon the 85 gasket to make a secure joint. When it is desired to unlock the parts the lever is turned in the direction of the arrow in Fig. 4 and the pivoted arm 5 swung in the direction of its arrow, and then the entire device 90 may be displaced from the jar top. In this way I provide a locking device which may be manipulated with facility and despatch, and which performs its functions in a comparatively perfect manner.

95 What I claim is:—

1. A locking device comprising a bridge piece with angular arms formed each with a hook and a beveled end, combined with a lever pivoted on the bridge piece having a 100

long arm and a short arm, and a third arm formed with a hook and beveled end and pivoted on the short arm of said lever.

2. A locking device comprising a single angular piece formed with end hooks and beveled ends, an operating lever having a long arm and a short arm pivoted centrally

of said piece, and an arm pivoted on the short arm of said lever having an end hook and beveled end and formed with a shoulder to provide a stop for said lever.

In testimony whereof I affix my signature.

EDGAR C. HILL.
